UNITED STATES PATENT OFFICE.

H. CLAY BASCOM, OF TROY, NEW YORK.

DESIGN FOR A HEATING-STOVE.

SPECIFICATION forming part of Design No. 14,486, dated December 18, 1883.

Application filed November 5, 1883. Term of patent 7 years.

To all whom it may concern.

Be it known that I, H. CLAY BASCOM, of Troy, in the county of Rensselaer and State of New York, have invented a certain new and useful Design for Heating Stoves; and I do hereby declare that the following is a full, clear, and exact description thereof, reference being had to the accompanying cut, print, or engraving of a stove having said new design.

My design embraces a stove which in horizontal section has an oblong form, and vertically is composed of a base, an ash-pit section, a fire-pot section, a combustion-chamber section, a magazine-section, and a top.

The design for the base A consists, substantially, of a flat rectangular plate, a , having smooth vertical edges a' , that terminate in an outward and downward inclined band, a'' . Below said band a'' is a depending flange, a^3 , which has an irregular ornamental outline at its lower edge, and upon its face is provided with ornamental figures, either in relief or intaglio. At each corner of said flange a^3 is a sustaining-leg, a^4 , which has the outline and surface ornamentation, all substantially as shown in the annexed cut.

The design for the ash-pit section B consists of vertical walls that are arranged in an oblong form, and each of the same is provided with a panel, b , which is ornamented substantially as shown, and may constitute a hinged door. The top of said ash-pit section is formed by a substantially flat projecting plate, b' , the edge of which b' is smooth and overhangs the walls of said section, and has a slight outward as well as a downward inclination. The design for this section also embraces a horizontal rail, b^4 , which extends from the front corners of the same, midway between its upper and lower ends, forward and across the front, all substantially as shown in the annexed cut.

The design for the fire-pot section C consists of four corner-posts, c , that have the form of a right angle in horizontal section, and between the same, upon the front, and at each end of said section, are provided mica doors c' , each of which has two light-openings, that are substantially square, with cut-away corners. The frames of said doors are extended outward, so as to form of each a raised panel hav-

ing beveled beaded edges c^2 , which are plain, while surrounding each of said light-openings is a beveled ornamented edge, c^3 . From the front side, at the lower end of said section C, 55 a plate or hearth, c^4 , extends forward to or beyond the front edge of the plate b' , and has its edges c^5 , which are smooth, rounded outward and downward, while its surface within said edges is ornamented. At the upper end of 60 each side of said section C is a horizontal ornamental band, c^6 , which separates the same from the combustion-chamber section next above, all substantially as shown in the annexed engraving.

The combustion-chamber section D is similar to fire-pot section C, before described; but its doors d have each four light-openings. At the upper end of said section D an ornamental band, d' , extends horizontally across each side 70 between the corner-posts c , and above the same is a horizontal plate, d^2 , which projects outward, and has a plain nearly vertical overhanging edge, d^3 . The upper surface of said plate is curved upward and inward and is 75 ornamented, all substantially as shown in the annexed print.

The magazine-section E has in horizontal section the general rectangular shape of the other sections, but is somewhat smaller than the combustion-chamber section. It has four plain right-angled corner-posts, e , which extend from the plate e^3 upward to the projecting top plate, F , and at their upper ends curve outward to the edge f of the same. Between said corner-posts, at each end and in front, is a panel, e' , which is ornamented by incised or raised lines, and at the upper edge of the same is an outward and upward curving band, e^2 , having a plain surface, all substantially as shown in 90 the annexed cut.

The top plate, F , has a plain, nearly vertical overhanging edge, f , from which there is a narrow horizontal ledge, f' , from which a plain band, f^2 , slopes upward and inward. Above 95 the band f^2 is an inward and upward sloping ornamental band, f^3 , and above the same a rectangular elevated central part, f^4 , which has a convex ornamented surface and plain inward and downward inclining edges f^5 , all substantially as shown in the annexed print.

Above the plate F is located an ornamental

horizontal handle, G, which is supported at its center by an ornamental post, g, all as represented in the annexed drawing.

Having thus described the nature of my invention, what I claim as new is—

1. The design for a heating-stove, embracing the sections A, B, C, D, E, and F, substantially as shown.
2. The design for a base A, embracing the plate a, having the edges a' a'', and depending flange a'', substantially as shown.
3. The design for an ash-pit section, B, embracing the panels b, plate b', having the overhanging edge b'', and the rail b'', substantially as shown.
4. The design for the fire-pot section C, embracing the corner-posts e, the mica doors e', having the beaded edges e'', and beveled edge light-openings e'', the hearth e'', having the ornamented upper face and rounded edge e'', and the ornamental band e'', substantially as shown.

5. The design for the combustion-chamber section D, embracing the corner-posts e, panels e', and concave band e'', substantially as shown.

6. The design for the magazine-section E, embracing the corner-posts, e, panels e', and concave band e'', substantially as shown.

7. The design for the top plate, F, embracing the overhanging edge f, the ledge f', the inclined band f'', the ornamental band f'', and the elevated central part, f' f'', substantially as shown.

8. The design for the handle G and supporting-post g, substantially as shown.

In testimony that I claim the foregoing I have hereunto set my hand this 3d day of November, 1883.

H. CLAY BASCOM.
